UNITED STATES PATENT OFFICE.

WILHELM VASSEN, OF AACHEN-FORST, GERMANY.

ROLLING-MILL.

1,025,078.

Specification of Letters Patent.

Patented Apr. 30, 1912.

Application filed September 8, 1910. Serial No. 581,029.

To all whom it may concern:

Be it known that I, WILHELM VASSEN, a subject of the Emperor of Germany, and residing at Stumpergasse 42, Aachen-Forst, Germany, have invented certain new and useful Improvements in Rolling-Mills, of which the following is a specification.

This invention relates to a rolling process and rolling machinery for rolling bars and columns of H and I cross section with parallel flanges, and embraces the devices employed for the production of the desired H or I shaped sections with parallel flanges and the construction of the rolling mill for the same purpose.

In the drawings Figure 1 is a view of a mill, partially in section, and partially in elevation to illustrate the arrangement of the first set of rolls. Fig. 2 is a horizontal section on the line 2—2, Fig. 1. Fig. 3 is an elevation of the set of rolls shown in Fig. 1. Fig. 4 is a view illustrating a balancing device for the horizontal shafts. Figs. 5, 6, 7, and 8 illustrate conventionally the several sets of rolls between which the bar passes. Fig. 9 is a detail vertical section on the line 9—9 of Fig. 10. Fig. 10 is a horizontal section on the line 10—10, Fig. 9. Fig. 11 is a transverse section on the line 11—11, Fig. 10. Fig. 12 is a diagrammatic view of an elevation of a complete mill. Fig. 13 is a similar view showing a plan view of the same.

Bars of H and I cross section with parallel flanges are in the first place rolled out in bent up form from rectangular blocks by means of a four roller block rolling mill whose rollers are adjustable on all sides from one point as shown in Figs. 1-3 and 40 Fig. 5 of the drawings, this rolling being carried out in such a manner that the side rolling faces of the vertical rollers b penetrate into the shorter sides of the block being rolled and are inclined to each other at 45 as acute an angle as possible between 60° and 90°, while the horizontal rollers b' which lie in the same plane simultaneously work into the longer side of the block. By further rolling in following sets of rollers 50 the corners of the block are rolled out and broadened. As the pass of the four rollers is open at the four corners the edges of the flanges are not operated upon so that nothing stands in the way of their free extension. After this H profile has been rolled 55 out in the manner hereinbefore described,

the bar is placed between a set of rollers of the kind illustrated in Fig. 6, which for convenience of arrangement is constructed in the same manner as the four roller block 60 rolling mill of Fig. 1 of the drawings. One difference however consists in that the rolling faces of the side rollers b intersect each other at an angle lying between 120° to 135°. By adjusting the four rollers which 65 may be effected from one point by a motor, the rollers are caused to uniformly approach each other and the H profile rolled out to the desired size.

The working of the edges is accomplished 70 by means of the pair of rollers shown in Fig. 7, which may be before or behind the last described set of rollers and are capable of being adjusted simultaneously in known manner. These rollers consist of a central 75 part b² having an undercut side roller face y on each side whereby a free space x is formed which allows of the thickening of the ends of the flanges produced by the rolling of the metal. Each of the side rolling 80 faces y is inclined in such a manner that the angle between it and the flange is somewhat less than 90° whereby bending together of the flanges is avoided.

After the bar has been provided with the 85 bent up section and its edges worked upon as described, it is passed through the straightening rollers of Fig. 8. The latter also consist in a set of four rollers—namely, the horizontal rollers b' and the vertical rollers b—90 which are adjustable on all sides by means of pressure screws, and in which the section is straightened up.

The sets of four rollers have roller standards z, cast laterally on which are inclosed 95 standard heads z' in which are arranged the mountings for the vertical rollers which are shown more in detail in Figs. 9, 10, and 11. The mounting a carries the vertical roller b which latter is journaled therein in the 100 bearing c. At its upper and lower sides the mounting is provided with guide flanges d in which are arranged the adjusting screws e. The points of these latter are let into the sliding fillets f to prevent their wearing 105 away. The screw heads are provided with flanges g on which a securing plate h with hexagonal holes corresponding in size to the screw heads is laid. By means of these adjusting screws the vertical rollers are adjustable in vertical direction.

The mounting is connected with the end

- of the horizontal pressure screw s by means of a head l on the pressure screw which is embedded in a suitably formed recess in a cross piece k which is formed in two parts held together by screws k' . This cross piece is also connected to the mounting a by means of two adjusting screws l having retaining collars l' likewise embedded in the cross piece. In order to prevent the tendency of the cross piece to bend it is supported near the pressure screw by means of a wedge m . By means of this construction the vertical rollers can be adjusted in a horizontal direction.
- 15 The upper horizontal roller is suspended by means of suspensory screws b' . (see Fig. 3) from two cross pieces u which are journaled on the head of the vertical pressure screws t , which suspensory screws connect the bearing forks v of the rollers with the cross pieces. On the top of the vertical pressure screw is situated a roller m' on which is wound up a cord c' supporting the index bob d' of a scale c' for the adjustment of the rollers. This cord passes over two further rollers f' to the scale situated on one of the roller standards z , on which scale the index bob indicates the amount of movement of the pressure screw and gives information of the position or distance apart of the rollers.
- 20 The rollers are adjusted simultaneously by means of the shaft 2, which carries bevel wheels 3 and 4, and worms 5 and 6. The bevel wheels 3 and 4 gear with the bevel wheels 7 and 8 mounted on shafts 9 and 10 respectively, and the worms operate the screws t through spiral gearing 18 and 19. The shaft 9 carries a worm 11 which operates one of the screws s through spiral gearing 13, and the shaft 10, in a similar manner, operates the other pressure screw by means of a worm 12. The shaft 10 drives, by means of bevel wheels 14, and 15, the shaft 16 which carries worms 17 and 20 operating the pressure screws of the lower horizontal roller through spiral gearing 22 and 21.
- 25 As the two horizontal rollers of the set of four rollers are simultaneously adjusted, it is necessary to provide the driving spindles n and o with a suitable balancing device as shown in Fig. 4. For this purpose the lower driving spindle o is somewhat heavier than the upper one n . At the upper part of both side cheeks of the spindle bracket g' are mounted two fixed rollers p . The brackets g for the bearing forks r of both driving spindles are connected to each other on both sides by means of a wire rope or chain, which passes over the fixed roller p and which possesses an adjusting device. The somewhat heavier lower driving spindle o lifts up the upper one, so that these both move automatically when adjusting the horizontal rollers.
- 30 In order to introduce work pieces of varying breadth of flange (which may be between 200 and 700 millimeters), into the pass of the set of four rollers or that of edge rolling rolls at the correct height it is necessary that the sets of rolls adjacent thereto should be adjustable in order to facilitate the entry of the bar being rolled.
- 35 Having now described my invention what I claim as new and desire to secure by Letters Patent is:
- In a method of rolling girders, columns, and the like pieces of **H** and **I** cross section with parallel flanges, passing a blank consisting of a block of rectangular cross section through a four roller block rolling mill whose rollers are adjustable on all sides and whose passes are open at the four corners, and in which the block is given a cross section with flanges inclined to each other at 60° to 90°; passing the bar through a second similar set of rolls in which the flanges are flattened out to 120° to 135°; operating upon the edges of the flanges in another set of rolls; and straightening out the flanges and 40 finishing the bar in a final set of four rollers with cylindrical vertical rollers.
- 45 In testimony whereof I have signed my name to this specification in the presence of two subscribing witnesses.

WILHELM VASSEN.
